(57) **CLAIM**

The ornamental design for a swivel mount with arms, as shown and described.

DESCRIPTION

FIG. 1 is a front perspective view taken from the top left corner of a two-arm swivel mount;

FIG. 2 is a rear perspective view taken from the top right corner thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof;

FIG. 8 is a bottom plan view thereof;

FIG. 9 is a rear perspective view taken from the bottom right corner thereof; and,

FIG. 10 is a rear perspective view taken from the top left corner thereof.

The broken line showing of the swivel mount with arms is for the purpose of illustrating portions of the swivel mount with arms and forms no part of the claimed design.

1 Claim, 10 Drawing Sheets
